COIN SLIDE DEVICE

Guy O. Leggett, North Tonawanda, N. Y., assignor to The Rudolph Wurlitzer Company, North Tonawanda, N. Y., a corporation of Ohio

Application September 7, 1937, Serial No. 162,642

18 Claims. (Cl. 194—97)

This invention relates to certain new and useful improvements in coin-controlled devices or mechanisms and more particularly to a structure which will reject or refuse slugs and like coin imitations.

One of its objects is to provide a coin-controlled mechanism of this character which is so designed and constructed as to effect a scanning test or examination of the coin or slug inserted in the device to thereby govern the operation or inoperation of the coin-controlled mechanism, depending upon whether a genuine or acceptable coin has been inserted or whether an attempt has been made to pass a slug or other unacceptable coin through the device.

Another object of the invention is to provide a reliable and efficient coin-controlled mechanism of the coin-advancing slide type having revolving coin-scanning means associated therewith for governing and predetermining the proper movement or obstruction of the coin slide and thence the operation or non-operation of the apparatus to which the coin slide structure is applied.

A further object is to provide a coin-controlled device embodying leveling means for testing contact with the surface contour of a coin or slug to govern and control the operative or non-operative movement of the coin-advancing slide as determined by the structural characteristics of the coins or slugs inserted in the slide.

Other features of the invention reside in the construction and arrangement of parts herein-after described and particularly pointed out in the appended claims.

In the accompanying drawings:

Figure 1 is a side elevation of the coin-controlled mechanism embodying my invention. Figure 2 is a top plan view thereof. Figure 3 is a bottom plan view of the same. Figure 4 is a longitudinal section taken substantially in the plane of line 4—4, Figure 2. Figure 5 is an enlarged longitudinal section, similar to Figure 4, but showing an acceptable coin advanced in the slide to the scanning position. Figure 6 is a similar view showing the coin slide advanced to its full stroke position to discharge an accepted coin. Figure 7 is a transverse vertical section taken on line 7—7, Figure 5. Figure 8 is a transverse vertical section taken on line 8—8, Figure 6. Figures 9 and 10 are horizontal sections taken on the correspondingly numbered lines in Figure 5. Figure 11 is a distended perspective view of the leverage mechanism for actuating the drum-locking pin. Figure 12 is an enlarged bottom plan view of the coin-slide frame showing, in section,

the latching means associated with the coin slide. Figure 13 is a fragmentary longitudinal section, similar to Figure 5, showing the disposition of the parts when an unacceptable coin is contained in the coin slide. Figure 14 is a fragmentary bottom perspective view of the coin slide. Figure 15 is a similar view of the coin-engaging platform which engages the bottom of the coin slide. Figure 16 is a fragmentary perspective view of the coin-slide and scanning means carrier or secondary slide showing the connection therebetween for effecting the independent advancement of the slide relative to the carrier as well as for effecting the retraction of the carrier simultaneously with the coin slide.

Similar characters of reference indicate corresponding parts throughout the several views.

In its general organization my improved coin-controlled mechanism comprises a body or guide member in which a coin-receiving or advancing slide is mounted for properly delivering acceptable coins to a point of discharge and thereupon initiate the action of the vending machine, phonograph or like apparatus to which the mechanism is connected; a revolvable scanning device or means associated with the coin slide and designed to test or examine the coin or slug inserted in the slide for acceptance or rejection, such means acting to govern and control the operative or non-operative movement of the coin-advancing slide as determined by the structural characteristics of the coin or slug attempted to be passed through the device.

Referring now to the drawings, wherein a preferred embodiment of my invention is illustrated, 15 indicates a channeled body, frame or guide member having a discharge opening 16 at its rear end for the discharge of an acceptable coin, while 45 forwardly of this opening the bottom side of the guide member has an opening 17 which is substantially cross-shaped in plan and includes a main rectangular-shaped portion and lateral portions 18 extending outwardly from the longitudinal side edges of the main portion of such opening. Adjacent its front or outer end the guide member has an attaching plate 19 for securing it to the coin-controlled apparatus. Slidably mounted on this guide member is the coin-

55

receiving or advancing slide 20 having an aperture 21 therein for the reception of a coin, the coin being supported on the floor or bottom of the guide member during the movement of the slide.

5 Also guided in the body member in that portion thereof rearwardly of the attaching plate 19 and disposed immediately over the adjoining rear portion of the coin slide 20 is a secondary slide or carrier 22 for the scanning device, which, during

10 the initial stroke of the coin slide, is held against movement relative thereto and which during the remaining stroke of the coin slide is adapted to be coupled thereto to move simultaneously therewith for a purpose which will hereinafter appear.

15 Adjacent its front end this secondary slide is provided with a circular opening 23 of smaller diameter than the coin slide aperture 21, and rearwardly of this opening such secondary slide has a longitudinal slot 24 into which extends a

20 stop element or screw stud 25 borne by the coin slide, this stud abutting against the front end of such slot in the fully retracted position of the coin slide shown in Figure 4. A similar stop element 25^a abuts against the rear end of such slot in the initial advanced position of the coin slide, so that upon the final stroke of the coin slide the secondary slide will move simultaneously therewith. It might be stated here that after

25 a coin is inserted in the coin slide and the same advanced to the aforesaid initial position in which the stop 25^a abuts the front end of the secondary slide notch 24, the coin is positioned axially of the circular opening 23 of the secondary slide, at which time the coin is forced up-

30 wardly by means hereinafter described, into surface contact with a roughened or radially-serialized coin-receiving recess 23^a formed in the bottom side of the secondary slide 22 about its opening 23, whereby the coin is bridged between

35 the latter and the coin slide to move jointly therewith and at the same time be held against turning. In this position, the coin is set for a scanning test or examination to determine by the nature of the coin whether it is acceptable or not.

40 If acceptable, the coin slide may then be advanced its final stroke to discharge the coin through the opening 16 of the guide member, and if not acceptable, the scanning means operates to prevent any appreciable further advance

45 of the coin slide and acts to effectually latch the coin slide against any movement to advance it to a coin-discharging position.

The scanning means, which is associated with the coin slide and by test or surface examination of the coins predetermines and governs the proper movement or obstruction of the coin slide depending on whether an acceptable coin or non-acceptable coin or slug is inserted in the coin slide, respectively, is indicated generally by the

50 numeral 26 and is superposed over the coin slide for relatively revolvable and simultaneous longitudinal movement therewith when an acceptable coin is inserted in the coin slide. When coins are not accepted under test by the scanning

55 means, the scanning device is held or clutched against turning and operates to automatically effect a latching of the coin slide and prevent its full operative stroke to thereby thwart attempts of unscrupulous persons to operate the apparatus to which the coin mechanism is applied by using spurious coins and slugs. In its preferred construction shown in the drawings, this scanning means is constructed as follows:

The numeral 27 indicates a revolvable drum

60 or cylinder provided at its upper end with a

cover 28 having a depending lug 29 at its periphery engaging a corresponding notch 30 in the upper edge of the drum, whereby the cover is compelled to revolve with the drum. At its lower end this drum is provided with a gear 31 and a depending hub 32 which engages the circular opening 23 of the secondary slide 22, the gear and hub forming a downwardly-facing shoulder 33 which bears on the top side of the secondary slide and supports the drum against downward displacement. The drum cover, hub and gear constitute in effect a unitary structure. Extending through the cover 28 axially of the drum is a journal pin 34 which constitutes an upper bearing for the drum and its upper end is provided with a slotted-head 35 in which is seated a tongue 36 of a bracket 37 whose upper end overhangs the drum in the manner shown in Figures 4, 5 and 6, and whose lower end or base-flange 38 is attached to the top side of the secondary slide 22 by screws 39 or like fasteners. A washer 40 applied to the journal pin 34 and interposed between the top side of the cover and the pin-head serves to support this journal pin in its proper relative position to the drum. By this construction the bracket and journal pin provide a firm support for the upper end of the drum 27 and the tongue connection 36 between the bracket and the journal pin holds the latter against rotation, this pin being provided immediately below the cover with a clutching disk 41 fixed thereto and having a plurality of radially-spaced teeth or stop elements 42 on its bottom side. As will hereinafter appear, the coin-scanning mechanism carried by and housed within the drum 27 includes a part which is adapted to cooperate with one or another of these teeth to prevent rotation of the drum and its associated parts and in turn obstruct a full stroke movement to the coin slide 20.

45 Disposed at one side of the channel body 15 rearwardly of its attaching plate 19 is a shiftable tappet bar 43 preferably of angle shape in cross section, the top flange thereof overhanging the top side of the secondary slide 22 and having a longitudinal row of teeth 44 thereon forming a gear rack with which the gear 31 of the drum 27 is adapted to engage to either roll thereover or be clutched therewith. The gear rack is of a length to permit an operative turning movement of the drum and a longitudinal movement of the coin slide from the initial point of the scanning examination or test station shown in Figure 5 to the point of coin discharge shown in Figure 6. The depending flange of this rack bar is provided adjacent its opposite ends with longitudinal slots 45 with which screws 46 borne by the slide body engage for limiting the fore and aft movement of the rack bar relative to the slide body. A coil spring 47 arranged in a

50 pocket 48 formed in the contiguous faces of the rack bar and slide body and abutting at its opposite ends against opposing lugs 49 formed on the parts, respectively, serves to constantly urge the rack bar to a retracted normal rearward position with the front end of its slots 45 abutting the stop screws 46. The rear end of the rack bar 43, at a predetermined time and under certain conditions in the movement of the coin slide and associated parts, is adapted to engage a

55 normally-released trip dog 50 pivoted adjacent the front end of the slide body 15 in the path of travel of the rack bar for shifting such dog into latching engagement with one or another of a series of teeth 51 formed in the adjoining lon-

60 75

5 longitudinal edge of the coin-advancing slide 20 to thereby arrest the coin slide and prevent its full operative stroke when the rack bar effects the tripping of the dog. A spring 52 applied to the dog normally holds it clear of the adjoining teeth 51 in the coin slide.

Housed within the drum 27 is a leverage mechanism for controlling the movements of a locking pin or clutching element 53 into and out of coupling engagement with the toothed disk 41, such leverage mechanism being designed for actuation or governed in its movements by the surface contour or other characteristics of coins or slugs to effect a sufficient operative movement to the pin 53 to clutch it with the toothed disk, as in the case of a spurious or unacceptable coin or slug, or to fail to impart a sufficient operative stroke to such pin to bring it into clutching engagement with the toothed disk, as in the case of a genuine or acceptable coin. In its preferred construction this leverage mechanism consists of three levers 54, 55 and 56 disposed side by side within the drum 27 for vertically-swinging movement, the levers 54 and 56 being pivoted at 57 to a pivot lug 58 depending from one side of a plate 59 supported within the upper portion of the drum below the toothed disk 41 and having a key or like connection 60 with the drum to turn therewith. The lever 55 which is disposed centrally of the drum between the companion levers 54 and 56 is pivoted at 61 to the opposite side of the plate 59 on a depending lug 62. The locking pin or clutching element 53 is mounted on the free end of the lever 54 and is guided in its vertical movements in an opening 63 formed in the lever-supporting plate 59. A spring 64 is arranged in bearing contact with the lever 54 and tends constantly to swing it downwardly to a position where its locking pin 53 is out of clutching range with the depending teeth of the disk 41. Adjacent its pivoted end such lever 54 is connected by a pin 65 and slot 66 with the adjoining free end of the intermediate lever 55. The lever 56 has a lateral offset or arm 67 at its free end which normally overhangs and contacts with the short arm 68 of the intermediate lever 55. A spring 69 in bearing engagement with the free end of the lever 56 constantly urges such lever to swing downwardly, and in so doing urges the intermediate lever 55 to swing upwardly, the spring 69 being of greater tension than the lever-engaging spring 64 to normally exert a pressure on the lever 56 and on the corresponding levers 55 and 54 through the contacting arms 67, 68 and the pin and slot connection 65, 66 to hold the lever 54 upwardly with its locking pin 53 projected into the path of the teeth 42 of the disk 41. By the pivotal and bearing contacts of the respective levers 54, 55 and 56, the degree of movement resulting from the scanning tests and imparted to the respective levers, say, from the lever 56 to the pin-carrying lever 54 or from the intermediate lever 55 to such pin-carrying lever, is effectually multiplied so that a very small degree of movement imparted to the aforesaid levers transmits a relatively long degree of movement to the locking pin 53 in retracting it from or projecting it into clutching engagement with the toothed disk 41.

The coins inserted in the coin slide serve, through intermediate means or elements directly acted upon by the coin, to control or govern the leverage mechanism 54, 55, 56 to in turn effect the projection or withdrawal of the locking
75

pin 53 to or from the toothed disk to clutch the scanning drum against turning or permit its turning to effect a complete operative stroke of the coin-slide, the surface contour or characteristic of any particular coin whether acceptable or unacceptable predetermining the movement imparted to the clutching pin. One of the means employed for this purpose consists of a leveling unit for scanning the surface-contour of the coin and comprises a plurality of headed upright pins 10 whose shanks engage corresponding openings 11 formed in the bottom or hub of the drum 27 and whose heads are arranged in a well or recess 12 provided by an annular flange 13 rising from the top face of the bottom wall of the drum. By preference, three or these pins are employed and are spaced equidistant from one another about the turning axis of the drum, with their heads normally supporting the pins in their lowered position, such pins normally seeking such position by gravity where they are in position to be acted upon at their lower ends for upward displacement by the coin. Disposed over and in registering relation with the heads of these pins is a three-armed leveling plate or spider 74 whose ends terminate in tongues 75 seated in upwardly-facing guide notches 76 formed in the annular flange 13, whereby this spider is held in proper relation to the respective leveling pins, the heads of the latter contacting the bottom side of the spider in the normal seated or lowered position of the latter so that any lift transmitted to the respective pins due to the uneven surface contour of the coin is immediately transmitted to the spider to accordingly change its elevation. Any appreciable movement transmitted to the spider—as for example, if the surface contour of a coin be such as to lift all three pins and accordingly elevate the spider uniformly vertically or substantially so—is in turn transmitted to the leverage mechanism 54, 55 and 56 and to this end the centrally-disposed lever 55 has a depending lug 77 thereon which normally contacts the center of the leveling spider 74. Any change in elevation transmitted to the spider imparts an upward movement to the lever 55 and a corresponding movement to the adjoining connected lever 54 to project the locking pin, should the displacement be sufficient to do so, into clutching engagement with the toothed disk 41. Should the surface character of the coin be such as to effect an elevation of but one or two of the leveling pins 10, the degree of angular displacement transmitted to the spider or leveling plate 74 is very slight at the center thereof and is not sufficient to project the locking pin into its clutching position, indicating that the coin is of an acceptable type, insofar as its surface-test is concerned, to pass through the machine. Primarily these leveling pins operate on other than genuine or acceptable coins to effect a sufficient elevational displacement of the spider to project the locking pin 53 into clutching engagement with the toothed disk 41 to hold the scanning drum 27 against turning, thereby preventing the full operative stroke being transmitted to the coin slide 20 and rejecting such slug or unacceptable coin.

Disposed centrally in the bottom or hub portion of the drum 27 and freely guided in an opening 78 therein is an axially-disposed center pin 79 which projects through the bottom of the drum in the same manner as do the leveling pins 70 and which terminates at its upper end in a laterally-extending arm or head 80 normally rest-

ing on the bottom of the recess 72 and extending sufficiently beyond and radially between adjoining intersecting arms of the spider 74 to be exposed therebetween for contact with a depending lug 81 projecting from the lever 56. It will be noted in Figures 5 and 6, that this center pin arm is of less height or thickness than the heads of the leveling pins 70, so that in its normal position, with no coin in the coin 10 slide, the top side of the arm is spaced from the bottom side of the spider 74. The spring 69 applied to the lever 56 normally urges such lever to swing downwardly with its lug 81 in bearing or abutting contact with the center pin. When 15 a coin or slug of a thickness approximating that of an acceptable coin reaches the station of test, the center pin is shifted upwardly a distance approximating or less than the height of the heads of the leveling pins 70 so as not to disturb the spider 74, resulting in the lever 56 being swung upwardly against the resistance of its spring 69 in contact with the bottom side of the plate 59, whereupon the spring 64 associated with the locking-pin lever 54 acts to force such lever 20 downwardly to retract the locking pin 53 from clutching engagement with the toothed disk 41. Should the coin inserted in the coin slide be of less thickness than that of an acceptable coin, then there is not sufficient movement transmitted 25 to the center pin 79 to disturb the lever 56 a sufficient amount to effect the retraction of the locking pin from the toothed disk, whereupon the scanning drum 27 is held against turning and the thin coin or slug attempted to be passed 30 through the machine is rejected.

It will be understood from the foregoing that the scanning operations performed by the pins 70 or the center pin 79 may be independent or joint, depending on the characteristics of the 40 particular coin inserted in the coin slide.

Certain types of slugs in circulation have embossments, such as lettering or ornamental figures, disposed in annular fashion on their opposite faces and adjacent the peripheries thereof, 45 and while they may or may not pass the surface-contour scanning test performed by the leveling pins 70 and the thickness test performed by the center pin 79, in conjunction with the leverage mechanism 54, 55 and 56, I provide a frictional scanning or testing means operative on such slugs to positively reject them and prevent the coin-slide advancing its full stroke. This frictional scanning means is designed to frictionally grip or clutch the slug or spurious coin of this type in such a way as to hold the scanning drum 50 27 against turning, as does the locking pin 53, and thus prevent a coin-discharge stroke being transmitted to the coin slide 20. In the preferred construction of this scanning means shown 55 in the drawings, it consists of a plurality of yieldable friction pins or elements 82 guided for vertical displacement in openings 83 formed in the bottom or hub portion of the drum and interposed radially between the leveling pins 70 but on a greater circumference where they are 60 in a position for operating upon the marginal or rim portion of the coin-surface. At their lower coin-engaging ends these friction pins have knife-like edges 84 disposed radially relatively to the drum-axis or coin for gripping or clutching engagement between embossments on such coin. Yieldable hangers 85 substantially in the form of leaf springs serve to support the friction pins 65 82 from the drum and hold them against turn-

ing and tend constantly to force such pins downwardly into firm gripping contact with a coin.

During the scanning test of a coin, that is, after its insertion in the coin-slide 20 and its advancement to the testing station axially below the scanning drum 27, the coin is forced upwardly by spring pressure against the scanning elements 70, 79 and 82 by means of a platform preferably in the form of a channeled plate 86 arranged in the cross-shaped opening 17 of the guide body 10 15 and supported or fulcrumed at its rear end on a ledge 87 formed in such body, while its opposite end is free to permit a vertical displacement of the plate. The flanges 88 of this channel plate engage corresponding longitudinal 15 grooves 89 in the coin slide 20 and the bottoms of these grooves constitute abutments and limit the upward displacement of the plate. Extending from its opposite sides the channel plate has bearing shoes or lugs 90 which register with the 20 lateral portions 18 of the body-opening 17 and in the retracted position of the coin slide bear against its bottom side outwardly of the grooves 89, as shown in Figure 3. Leading rearwardly 25 from the opposite marginal portions of the coin-slide aperture 21 and in the vertical plane of the plate-shoes 90 are longitudinal recesses 91 into which said shoes are adapted to drop when the coin-slide is advanced to the testing or scanning station and continue in engagement therewith for the balance of the slide stroke. The channel plate is constantly urged upwardly by a bowed spring 92 held in place by a cover plate 93 applied to the underside of the guide member 15. When the aperture of the coin slide reaches 30 a position just short of being in axial alignment with the scanning drum 27, the plate-shoes 90 are forced into the marginal portions of such opening by the spring 92, the coin engaging and straddling the flanges 88 of the plate 86 and 35 being forced by the latter firmly against the scanning pins 70, 79 and 82 and the serrated recess 23a of the secondary slide-opening 23. By preference, the bottom face of the drum-hub 40 32 through which the several scanning pins project is concave or arched in contour, extending inwardly from the serrated recess, as shown in Figures 5 and 6.

When the coin slide 20 has been advanced its full stroke to discharge an accepted coin, it is 45 desirable to effect the return of the secondary slide or carrier 22 simultaneously with that of the coin slide, and to this end the rear stop element 25a is attached to the free end of a laterally-movable spring arm 94 which may be 50 fixed at its opposite end to the companion stop element 25. The stop element 25a has a lateral extension 95 which abuts the opposing edge of the guide frame 15 during the major portion of the slide movement and at its front end the 55 carrier-slot 24 has an offset notch 96 into which the opposing edge 97 of said stop element is adapted to snap, by the pressure of its spring arm 94, when such element rides off the end of the chamfered edge 98 of the guide frame at the 60 final portion of the slide-stroke. The moment the stop element 25a encounters the notch 96, the carrier 22 is coupled with the coin slide, so 65 that when the latter is retracted the carrier moves simultaneously therewith until the scanning means 26 reaches its initial position, at which time the extension 95 of the stop element encounters the chamfered edge 98 of the guide frame, withdrawing such stop element from coupling engagement with the notch 96 and per- 70 75

mitting an independent movement of the coin slide to its initial position in readiness to receive another coin.

Briefly stated, the operation of the device is as follows:

A coin is placed in the coin slide in the usual fashion and the slide advanced rearwardly to the coin-testing station. If the coin is an acceptable one, the tests thereon will not in any way affect the projection of the locking pin 53, so that the toothed disk 41 will, during a further advance of the coin slide, permit the free turning of the drum with its gear 31 rolling over the teeth 44 of the tappet bar 43 until such time as the coin registers with the opening 18 when the coin will drop by gravity therethrough. Should the coin be an unacceptable one and the tests thereon at the testing station cause an elevational displacement of the locking pin 53 into clutching engagement with toothed disk 41, in the manner heretofore described, then the scanning drum 27 will be clutched against turning, thereby preventing a full operative stroke being transmitted to the coin slide and causing the normally-released trip dog 50 to be forced by the tappet bar 44 into latching engagement with one or another of the teeth 51 in the coin slide. When thus latched against movement, the user of the slide must retract the coin slide to its initial position because the slide will not function properly unless an acceptable coin is inserted in the slide.

I claim as my invention:

1. A coin device of the character described, comprising a frame, a coin-advancing slide guided in said frame, a locking detent normally disengaged from the coin slide and projectable into latching engagement therewith under certain conditions to prevent its full operative stroke, a tappet bar disposed in operative relation to said locking detent to project it into its latched position, and revolvable coin-scanning means operatively associated with the coin slide and adapted to actuate said tappet to render said detent operative to latch the coin slide when the coin scanned is unacceptable and to be ineffective on said tappet when the coin scanned is an acceptable one to permit a full operative stroke of the coin slide.

2. A coin device of the character described, comprising a frame, a coin-advancing slide guided in said frame, slide-latching means normally permitting a full operative stroke of the coin slide when an acceptable coin is inserted therein, and revolvable coin-scanning means disposed for movement with the coin slide and for operative engagement with a coin and including means for governing the rotation or non-rotation of said means depending upon the scanning test performed on an acceptable or non-acceptable coin, respectively, and means controlled by said scanning means and rendered operative by the non-rotation thereof during a partial stroke of said slide to actuate said latching means to prevent a full operative stroke of the coin slide.

3. A coin device of the character described, comprising a frame, a coin-advancing slide guided in said frame, slide-latching means normally permitting a full operative stroke of the coin slide when an acceptable coin is inserted therein, revolvable coin-scanning means disposed for movement with the coin slide and for operative engagement with a coin and including means for governing the rotation or non-rotation of such means depending upon the scanning test per-

formed on an acceptable or non-acceptable coin, and gear and rack means operatively connecting said scanning means and said slide-latching means and rendered operative when an unacceptable coin is inserted in said slide to actuate said latching means into operative engagement with the slide to prevent its full operative stroke.

4. A coin device of the character described, comprising a frame, a coin-advancing slide guided in said frame, a carrier slidably mounted in the frame above the coin slide and adapted for movement therewith, a connection between the slide and the carrier whereby the slide may move independently of the carrier for a portion of its stroke, a revolvable scanning means mounted on said carrier including elements engageable with the coin for testing its surface contour and a clutching device controlled thereby for governing the rotation and non-rotation of the scanning means as determined by the scanning test of an acceptable or non-acceptable coin, and means controlled by the rotation and non-rotation of said scanning means for respectively permitting and preventing a full operative stroke of the coin-slide.

5. A coin device of the character described, comprising a frame, a coin-advancing slide guided in said frame, a carrier slidably mounted in the frame above the coin slide and adapted for movement therewith, a connection between the slide and the carrier whereby the slide may move independently of the carrier for a portion of its stroke, a revolvable scanning means mounted on said carrier including elements engageable with the coin for testing its surface contour and a clutching device controlled thereby for governing the rotation and non-rotation of the scanning means as determined by the scanning test of an acceptable or non-acceptable coin, a normally disengaged latching means for the coin slide, and means controlled by said scanning means for rendering said latching means operable to prevent a full operative stroke of the coin slide when an unacceptable coin is inserted therein.

6. A coin device of the character described, comprising a frame, a coin-advancing slide guided in said frame, a carrier slidably mounted in the frame above the coin slide and adapted for movement therewith, a connection between the slide and the carrier whereby the slide may move independently of the carrier for a portion of its stroke, a revolvable scanning means mounted on said carrier including elements engageable with the coin for testing its surface contour and a clutching device controlled thereby for governing the rotation and non-rotation of the scanning means as determined by the scanning test of an acceptable or non-acceptable coin, a normally disengaged latching means for the coin slide, a gear applied to said scanning means, and a tappet bar for said latching means including a gear rack in operative engagement with said gear, the latter revolving freely over said rack to permit a full operative stroke of the coin slide when an acceptable coin is inserted therein and said gear being clutched to said rack, when the scanning means is rendered non-rotative, to shift the tappet bar to engage said latching means with the coin slide and prevent its full operative stroke when an unacceptable coin is inserted therein.

7. A coin device of the character described, comprising a frame, a coin-advancing slide guided in said frame, a carrier slidably mounted in the frame above the coin slide and adapted for move-

ment therewith, a connection between the slide and the carrier whereby the slide may move independently of the carrier for a portion of its stroke, a coin-scanning means mounted on said carrier for surface-contour-testing of a coin inserted in the slide, a normally disengaged latching means for said slide, a normally retracted tappet bar disposed in operative relation with said latching means and projectable to a position to engage the latter with said slide, and means engageable with said tappet bar and controlled by said scanning means for rendering such bar operative to engage said latching means with the coin slide to prevent its full operative stroke when an unacceptable coin is inserted therein and for rendering such bar unprojectable out of its normally retracted position when an acceptable coin is inserted in the coin slide.

8. A coin device of the character described, comprising a frame, a coin-advancing slide guided in said frame, a carrier slidably mounted in the frame above the coin slide and adapted for movement therewith, a connection between the slide and the carrier whereby the slide may move independently of the carrier for a portion of its stroke, coin-scanning means mounted on said carrier for rotative movement when the latter is moved with the coin slide, means for rotating said scanning means at a predetermined time in the movement of said slide, latching means normally disengaged from the coin slide to permit its full operative stroke when an acceptable coin is inserted therein, and means constituting a part of said rotating means and rendered operative 30 when an unacceptable coin is inserted in the coin slide for actuating said latching means into engagement with said slide to prevent its full operative stroke.

9. A coin device of the character described, comprising a frame, a coin-advancing slide guided in said frame, a carrier slidably mounted in the frame above the coin slide and adapted for movement therewith, a connection between the slide and the carrier whereby the slide may move independently of the carrier for a portion of its stroke, a coin-scanning means mounted on said carrier for rotative movement when the latter is moved with the coin slide, means for rotating said scanning means at a predetermined time in the movement of said slide including a gear on said scanning means and a slidable tappet bar mounted on said frame and having a gear rack thereon meshing with said gear, means for normally yieldingly resisting movement of said tappet bar, and latching means arranged in operative relation to said tappet bar and normally disengaged from the coin slide to permit its full operative stroke and that of the scanning means therewith when an acceptable coin is inserted in said slide, said tappet bar being disposed for joint movement with the coin slide and carrier when an unacceptable coin is inserted in said slide to actuate said latching means into engagement with said slide to prevent its full operative stroke.

10. A coin device of the character described, comprising a frame, a coin-advancing slide guided in said frame, a coin-scanning means disposed over the coin slide for relative rotation and longitudinal movement therewith during a portion of its stroke, means for rotating said scanning means during its movement with the slide, means governed by such scanning means in accordance with its coin-scanning tests for controlling the rotation or non-rotation thereof, and

means for automatically latching said coin slide against a full stroke movement when the scanning means is rendered non-rotative by reason of an unacceptable coin being inserted in the coin slide.

11. A device of the character described, comprising a frame, a coin-advancing slide guided in said frame, a coin-scanning means for detecting acceptable and unacceptable coins disposed over the coin slide for relative rotation and longitudinal movement therewith during a portion of its stroke, means for imparting rotary movement to said scanning means in response to such slide-stroke, a locking element actuated in response to the scanning tests and causing the scanning means to be held against rotation when an unacceptable coin is inserted in the coin slide and permitting rotation thereof when an acceptable coin is inserted therein, and means rendered operative when the scanning means is held against rotation and during a subsequent partial stroke of the coin slide for arresting the full operative stroke of such slide.

12. In a coin controlled device of the character described, the combination with a coin-advancing slide, of a scanning means operatively engageable with the coin during a portion of the slide-stroke for detecting acceptable and unacceptable coins and governing the movements of the coin-slide, comprising a revolvable drum having scanning elements protruding through its bottom for surface engagement with the coin, a clutching disk disposed axially of the drum and held against rotation relative thereto, a displaceable locking member revolvable with said drum and selectively movable into and out of engagement with said clutching disk, and means interposed between said scanning elements and said locking member for governing the displacement of the latter in accordance with the results of the scanning tests on the coin.

13. In a coin controlled device of the character described, the combination with a coin-advancing slide, of a scanning means operatively engageable with the coin during a portion of the slide-stroke for detecting acceptable and unacceptable coins and governing the movements of the coin slide, comprising a revolvable drum having scanning elements protruding through its bottom for surface engagement with the coin, some of said elements acting in response to the uneven surface contour of the coin and another in response to the thickness of the coin, means for releasably clutching the drum against rotation, displaceable means actuated by said respective scanning elements and operatively connected to said clutching means for governing the same to permit the free rotation of the drum should the coin tested be acceptable or to prevent rotation of the drum should the coin tested be unacceptable, and means for automatically latching the coin slide against movement when the drum is rendered non-rotative.

14. In a coin controlled device of the character described, the combination with a coin-advancing slide, of a scanning means operatively engageable with the coin during a portion of the slide-stroke for detecting acceptable and unacceptable coins and governing the movements of the coin slide, comprising a revolvable drum having scanning elements protruding through its bottom for surface engagement with the coin, said scanning elements being free to rise and fall in accordance with the surface contour of the coin and being disposed equidistant apart about the drum-axis,

a displaceable spider seated on the upper ends of said elements, means for releasably clutching the drum against rotation, an operative connection between said spider and said clutching means for governing the latter to permit or prevent the rotation of said drum in accordance with the results of the scanning test performed on the coin, and means for automatically latching the coin slide against movement when the drum is rendered non-rotative.

15. In a coin controlled device of the character described, the combination with a coin-advancing slide, of a scanning means operatively engageable with the coin during a portion of the slide-stroke for detecting acceptable and unacceptable coins and governing the movements of the coin slide, comprising a revolvable drum having scanning elements protruding through its bottom for surface engagement with the coin, said scanning elements consisting of yieldably supported pins having knife-like edges at their lower ends and adapted for frictional contact between surface projections of an unacceptable coin, means for holding the coin against relative rotation to said drum when in contacting relation with said scanning elements, and means for automatically latching the coin slide against movement when the drum is rendered non-rotative.

16. A coin device of the character described, comprising a frame, a coin-advancing slide guided in said frame, a carrier slidably mounted in the frame above the coin-slide and adapted for movement therewith, a connection between the slide and the carrier whereby the slide may move independently of the carrier for a portion of its stroke, said connection including means for coupling the carrier with the coin slide to effect a simultaneous retraction of such parts upon a full advance stroke of the coin slide, locking means for preventing a full operative stroke of said slide under certain conditions, and coin-scanning means mounted on said carrier for operative engagement with a coin for governing said locking means to control the movements of the coin slide.

17. A device of the character described, comprising a frame, a coin-advancing slide guided in said frame, a carrier slidably mounted in the frame above the coin slide and adapted for movement therewith, a connection between the slide and the carrier whereby the slide may move independently of the carrier for a portion of its stroke, said carrier having an opening therein and a serrated recess about the bottom edge thereof and against which a coin is adapted to be seated, a yieldable platform mounted in said frame and with which a coin is adapted to engage at a predetermined time in the movement of the coin slide for urging the coin against said carrier-recess and holding the coin against turning, a coin-scanning means rotatably mounted in said carrier opening for relative rotation and longitudinal movement with the coin slide during a portion of its stroke, said scanning means including a drum having a gear thereon and displaceable scanning elements projecting through the drum for surface contact with the coin, a shiftable latch controlling member for the coin slide applied to said frame and having a gear rack thereon for engagement by said drum-gear, a stationary clutch disk arranged axially of said

drum, means rotatable with the drum and projectable into and out of coupling engagement with said clutch disk for governing the rotation or non-rotation of the drum, means actuated in response to the scanning tests performed by said displaceable elements for bringing said coupling means into or out of clutching engagement with said disk, said coupling means being released from the disk when an acceptable coin is present in the coin slide to permit a free rotation of the 10 scanning means relative to said coin slide latch-controlling member and a full operative stroke of the slide, and said coupling means being engaged with the disk when an unacceptable coin is present in the slide to lock the scanning means 15 against rotation and during a subsequent partial stroke of the coin slide to urge said latch-controlling member in a direction to effect the latching of the slide to prevent its full operative stroke.

18. A coin-controlled device of the character described, comprising a frame, a coin-advancing slide guided in said frame and containing an aperture for a coin, a carrier slidably mounted on said frame over the coin slide and having a lost-motion connection therewith whereby the 20 slide may move part of its stroke while the carrier remains stationary, a dog engageable with the coin slide for preventing its movement under certain predetermined conditions, a spring normally urging said dog out of engagement with 30 said slide, a slide member having a gear rack thereon disposed alongside the coin slide for operative engagement with said dog to bring it into latching engagement with the coin slide, means for normally urging said slide member having a gear rack, a plurality of scanning pins extending through the bottom of said drum for surface 35 contact with a coin borne by the coin slide, means for displacing the coin upwardly against said pins and for holding the coin against turning relative to the scanning drum, a leverage mechanism applied to said drum to turn as a unit therewith 40 and including a displaceable locking element applied to one of the levers of said mechanism for locking said drum against turning when an unacceptable coin is placed in the coin slide, means disposed in displaceable contact with said scanning pins and said leverage mechanism for governing the movement of the locking element to its latched and unlatched positions in accordance 45 with the scanning test performed on the coin by said pins, said drum being free to move simultaneously with its carrier and the coin slide in rolling contact over the rack bar in the unlatched position of said locking element and being held against turning in the latched position of such element whereby the drum-gear is clutched 50 to said rack bar to actuate it, upon further advancement of the coin slide, to a position to shift the dog into latching engagement with the coin slide, and friction pins applied to and extending through the bottom of said drum for engagement 55 with embossed portions of unacceptable coins, whereby the drum is clutched against turning by such pins and coin and movement of the coin slide to its coin-discharging position is prevented.
